UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

MINING APPARATUS

Application filed November 25, 1929. Serial No. 409,565.

This invention relates to mining apparatus and more particularly, but not exclusively, to improved propelling mechanism for a coal mining apparatus of the wheel mounted type adapted to operate while supported on and guided by the mine trackway.

An object of this invention is to provide an improved coal mining apparatus. Another object is to provide an improved coal mining apparatus of the wheel mounted type adapted to operate while supported on and guided by the mine trackway and having improved propelling mechanism. Still another object is to provide an improved propelling mechanism for a mining apparatus of the aforesaid character which is supplemental to the usual truck wheel driving mechanism. Another object is to provide in a mining apparatus of the aforesaid character an improved haulage mechanism supplemental to the truck wheel driving mechanism for propelling the apparatus along the mine trackway, the said supplemental haulage means being operable wholly independently of the truck wheel driving mechanism. A further object is to provide an improved haulage means for a mining apparatus of the wheel mounted type including a power winding device and a cooperating draft element, the said haulage means supplementing the usual propelling mechanism for the apparatus. Yet another object is to provide an improved supplemental haulage means for a wheel mounted mining apparatus for propelling the latter along the mine trackway and including a plurality of independently operable winding devices and cooperating flexible draft elements whereby the usual truck wheel driving means may be supplemented. A further object is to provide a supplemental propelling means for a wheel mounted mining apparatus and including a flexible draft element connectible to an extraneous abutment whereby in case the tractive effort of truck wheel drive is insufficient to propel the machine with the necessary power, the same may be augmented or at times supplanted by the improved supplemental propelling means. These and other objects and advantages of this invention will, however, hereinafter more fully appear.

In the accompanying drawings there is shown for purposes of illustration one form which the invention may assume in practice.

In these drawings,

Fig. 1 is a plan view of a mining apparatus having the illustrative embodiment of the improved supplemental propelling means embodied therein.

Fig. 2 is a side elevational view of the mining apparatus shown in Fig. 1.

Fig. 3 is an enlarged horizontal sectional view taken substantially on line 3—3 of Fig. 2.

Fig. 4 is an enlarged transverse vertical sectional view taken substantially on line 4—4 of Fig. 2 with parts shown in elevation.

In this illustrative embodiment of the invention there is shown a mining apparatus of the wheel mounted universal type of the same general character as that disclosed in a copending application to one Morris P. Holmes, Ser. No. 187,600, filed Sept. 24, 1926, although it is evident that the improved supplemental propelling means may be utilized in an equally effective manner with mining apparatus of various other types. This mining apparatus generally comprises a frame 1 supported on adjustable front and rear supports 2 and 3 respectively herein comprising swingable arms and supported on truck wheels 4 adapted to run along a usual mine trackway 5. As described in the above mentioned copending application, the supports 2 and 3 may be adjusted either simultaneously or one independently of the other to effect adjustment of the frame 1 into different elevated positions relative to the trackway or to be tilted about a transverse axis to change its angle relative to the horizontal as conditions may require. Mounted on the frame 1 for rotation about a longitudinal axis within spaced bearing means 6 and 7 supported by the frames of the front and rear adjustable supports 2 and 3, respectively, is a frame or body 8. This body houses a motor 9 and supports at its forward end adjustable kerf cutting mechanism 10 including a usual swingable cutter bit carrying cutter bar. As the specific construction of the mechanism for rotating the machine body, for adjusting the cutting mechanism, and for driving and

operating the cutting mechanism do not enter into this invention, further description of the same is thought unnecessary. The motor 9 also drives, as hereinafter described, the 5 truck wheel driving mechanism generally designated 11 and the improved supplemental propelling means generally designated 12. Electrical energy is conducted to the electrical apparatus of the motor 9 through a usual 10 flexible conductor cable 13 wound upon a cable reel 14 mounted for rotation on the rear end of the frame 1 and this reel is also driven as described in the above mentioned application from the motor 9.

15 Now referring to the truck wheel driving mechanism 11 it will be noted that the armature shaft of the motor 9 (see Fig. 3) drives an alined shaft 20 which has secured thereto as by a key 21 at its rear end a spur pinion 22. 20 As illustrated, the pinion 22 meshes with a spur gear 23 suitably secured to a longitudinally extending shaft 24. Also secured to this shaft is a spur pinion 25 meshing with a spur gear 26 secured to a longitudinally extending shaft 27. These shafts are suitably 25 journaled within a transmission housing 28 suitably secured to the frame 1 and have secured thereto as by keys 29 worms 30 and 31 respectively. These worms mesh respectively 30 with coaxial fast and slow speed worm wheels 32 and 33 suitably journaled on anti-friction bearings 34 supported by a horizontal transversely extending shaft 35. This shaft is in turn journaled within anti-friction bearings 35 36 supported within the transmission housing 28 and the worm wheels 32 and 33 are alternatively connectible to the shaft 35 by means of friction disc clutches 37 and 38 respectively so that when the clutch 37 is applied the shaft 35 may be driven from the motor 9 at a relatively fast speed while when the friction clutch 38 is applied and the clutch 37 is released, the shaft 35 may be driven in the same direction at a relatively low speed. 45 In the present construction, secured as by a key 40 to the shaft 35 is a bevel pinion 41 meshing with reverse bevels 42 and 43 suitably journaled on anti-friction bearings 44 supported by a longitudinally extending shaft 45, in turn journaled within suitable 50 anti-friction bearings 46 supported within the transmission housing 28. These reverse bevels 42, 43 are alternatively connectible to the shaft 45 by means of friction disc clutches 55 47 and 48 respectively so that when one or the other of these clutches is applied, the shaft 45 may be driven in one direction or the other. As shown in Fig. 3, connected by a coupling 49 to the shaft 45 is an alined shaft 60 journaled at its forward end within an anti-friction bearing 51 supported by the frame 52 of the rear support 3. Secured as by a key 53 to the forward end of the shaft 50 is a bevel pinion 54 meshing with a bevel gear 65 55 rotatably supported by a transverse shaft

56. This pinion is journaled within anti-friction bearings 57 suitably supported by the frame 52. The bevel gear 55 is connectible to the shaft 56 by a jaw clutch device 58. As shown, secured to the shaft 56 by a key 59 70 is a chain sprocket 60 which is connected by an endless chain connection 61 (see also Fig. 4) to a chain sprocket 62 secured as by a key 63 to a transverse shaft 64. Also secured to this shaft is a chain sprocket 65 which is connected by an endless chain connection 66 to a chain sprocket 67 secured to the rear truck wheel axle 68. Also secured to the shaft 64 is a chain sprocket 69 connected by an endless chain connection 70 (see Fig. 2) to a chain sprocket 71 secured to a transverse shaft 72. This shaft is connected by a chain and sprocket connection 73 to the front truck wheel axle 74. It will thus be seen that when the clutch device 58 is in a position to connect the bevel gear 55 to the shaft 56 and one or the other of the clutches 47, 48 and 37, 38 are applied, the truck wheels may be driven in either of opposite directions from the motor 9 at either a relatively high transport speed or at a relatively slow cutting speed. It will herein be noted that secured as by a key 76 to the shaft 35 is a bevel pinion 77 meshing with reverse bevels 78 and 79, these bevels being alternatively connectible by friction clutches 80 and 81 respectively to a longitudinally extending shaft 82. The shaft 82 drives, in a manner clearly described in the above mentioned co-pending application, the mechanism for adjusting the supports 2 and 3. As this mechanism does not specifically enter into this invention, description of the same is herein thought unnecessary. The operating means for the clutches 37, 38, 47, 48, 58, 80 and 81 are also substantially the same as those described in the above mentioned Holmes application.

The improved supplemental propelling mechanism 12 for propelling the apparatus along the mine trackway includes haulage devices 83 and 84, herein each comprising a winding drum 85 and these drums have wound thereupon haulage cables 86 and 87 respectively. As the mechanisms for driving the drums 85 are similar in construction, a description of one will suffice for both. Referring to the driving mechanism for the drum 85 of the hauling device 83, it will be noted that meshing with the reverse bevels 42, 43 is a bevel gear 86 secured as by a key 87 to a horizontal transversely extending shaft 88 herein alined with the shaft 35. This shaft 88 is suitably journaled within a bearing sleeve 89 supported within a bearing bracket 90 secured as by screws 91 to one side of the transmission housing 28. Connected to the shaft 88 is a series of clutch plates or discs 92 which are interleaved with a corresponding series of clutch plates or discs 93 secured to a sleeve portion 94 preferably formed in

tegral with the drum. The drum 85 is journaled on spaced anti-friction bearings 95 supported by the bearing bracket 90. In the present construction, the mechanism for applying the clutch 92, 93 comprises a hand wheel nut 96 threadedly connected at 97 to the reduced threaded end of the shaft 88. Surrounding this shaft is an annular pressure plate 98 having inwardly projecting fingers 99 engaging the adjacent end disc of the clutch. Interposed between the hand wheel 96 and the pressure plate 98 is a ball thrust bearing 100. The hand wheel for operating the friction clutch controlling the winding drum 85 of the haulage device 84 is indicated at 101. It will thus be seen that when the friction clutch 92, 93 is applied, the winding drum 85 may be rotated in a direction to wind in its cooperating cable at either a relatively slow speed or a relatively high speed, depending upon which of the fast and slow speed controlling clutches 37 and 38 is applied. It will also be evident that by reversing the motor 9 the winding drums 85 may be rotated in a direction to pay out their cooperating cables at either a relatively high speed or a relatively low speed. When the drums are being driven at a relatively slow speed the cables are drawn in or wound in to propel the apparatus at substantially the same speed as that effected by the truck wheel drive, it being evident that the apparatus may be propelled along the mine trackway at a relatively slow cutting speed under the propulsion of either or both the truck wheel driving mechanism 11 and the supplemental haulage mechanism 12.

The operation of the improved mining apparatus will now be described. The apparatus may be propelled about the mine at a relatively high transport speed under the control of the fast feed control clutch 37 and the friction clutch 47. The truck wheels are driven from the motor 9 at a fast transport speed through the spur gearing 22, 23, worm gearing 30, 32, bevel gearing 41, 42, shafts 45, 50, bevel gearing 54, 55 and the chain and sprocket connections 61, 66 and 70. If it is desired to propel the apparatus along the mine trackway in a reverse direction at a relatively high speed, the friction clutch 47 is released and the friction clutch 48 applied, and as a result, the truck wheels are driven in the reverse direction. During the cutting operation, the cutting mechanism is operated to cut a kerf beneath the coal and the sumping and withdrawal cuts are effected by propelling the apparatus bodily along the mine trackway at a relatively slow cutting speed. The relatively slow speed drive of the truck wheels for propelling the apparatus forward along the mine trackway is effected by the motor 9 through transmission gears 22, 23, 25, 26, worm gearing 31, 33, bevel gearing 41, 42, friction clutch 47, shafts 45, 50, bevel

gearing 54, 55 and chain and sprocket connections 61, 66 and 70. The apparatus may be propelled rearwardly along the mine trackway simply by releasing the friction clutch 47 and applying the reverse friction 48, thereby effecting reversal of the drive. If, for any reason, the truck wheels slip relative to the track rails and their tractive effort is insufficient for propelling the machine along the mine trackway during the cutting operation, the truck wheel driving mechanism may be supplemented by the improved supplemental propelling means 12. When it is desired to propel the apparatus by means of either of the haulage devices 83, 84 the feed cable is unwound from the drum and extended to a point in advance of the machine as, for instance, anchored at its free end as shown in Fig. 1 to a roof jack or other suitable anchoring device. If it is desired to wind in the feed cable at a speed appropriate to effect propulsion of the machine at a cutting speed, the friction clutches 38 and 92, 93 are applied, thereby effecting rotation of the drum 85 in winding direction at a relatively slow speed. The winding drum may be operated to wind in the cable to effect propulsion of the apparatus along the mine trackway in the reverse direction simply by extending the cable in a rearward direction and anchoring the free end thereof to a roof jack or other suitable anchoring device located at the rear of the apparatus. It will also be evident that if desired the apparatus may be propelled along the mine trackway in either direction under the propulsion of both the haulage devices 83 and 84. These haulage devices 83 and 84 may also be utilized for propelling the apparatus upwardly along a steeply inclined trackway or under certain conditions to be utilized as a safety device for controlling movement of the apparatus downwardly along a steeply inclined trackway. It will also be evident that these improved haulage devices may be operated simultaneously with the truck wheel driving mechanism to supplement the truck wheel drive in case the truck wheels slip relative to the track rails or if desired, the haulage devices may be used to propel the machine wholly independently of the truck wheel drive. These haulage devices may also be utilized for "spotting" mine cars and for hoisting mine props or any other auxiliary work, thereby obviating the necessity of providing a separate haulage device for these purposes.

As a result of this invention it will be noted that an improved mining apparatus of the wheel mounted type is provided having improved propelling means. It will further be evident that by providing the supplemental propelling mechanism in a mining machine of the wheel mounted universal type, it is possible to supplement the truck wheel drive in case the truck wheels slip relative to the track

rails, for instance, when the machine is effecting its summing and withdrawal cuts or moving along a steeply inclined trackway. It will still further be noted that the improved winding devices may be utilized for auxiliary hoisting purposes, thereby obviating the necessity of a special hoisting device. It will also be noted that the improved supplemental propulsion mechanism may be embodied in a mining apparatus of a standard design with a minimum of change and expense. These and other uses and advantages of the improved mining apparatus will be clearly apparent to those skilled in the art.

15 While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

25 1. The combination with a mining apparatus of the wheel mounted type adapted to run along a mine trackway and having cutting mechanism adapted to operate while said apparatus is supported and guided by the mine trackway and mechanism for driving the truck wheels to propel the apparatus at a predetermined relatively low speed during the cutting operation and at a relatively high speed during transport, of supplemental propelling means for the apparatus to effect a continuous slow speed propulsion thereof appropriate for cutting and at substantially the same speed as said predetermined low truck wheel driving speed, said supplemental propelling means being operable independently of truck wheel drive.

45 2. The combination with a mining apparatus of the wheel mounted type adapted to run along a mine trackway and having cutting mechanism adapted to operate while said apparatus is supported and guided by the mine trackway and mechanism for driving the truck wheels to propel the apparatus at a relatively low speed during the cutting operation and at a relatively high speed during transport, of supplemental means for propelling the apparatus at substantially the same speed as said low truck wheel driving speed and operable independently of truck wheel drive and including a winding device and a cooperating draft element, said winding device being arranged on a horizontal axis at one side of the apparatus.

60 3. The combination with a mining apparatus of the wheel mounted type adapted to run along a mine trackway and having cutting mechanism adapted to operate while said apparatus is supported and guided by the mine trackway and mechanism for driving the truck wheels to propel the apparatus

during the cutting operation, of supplemental propelling means for the apparatus operable independently of truck wheel drive and including a plurality of independently or simultaneously operable winding devices and 70 cooperating draft elements.

4. The combination with a mining apparatus of the wheel mounted type adapted to run along a mine trackway and having cutting mechanism adapted to operate while said apparatus is supported and guided by the mine trackway and mechanism for driving the truck wheels to propel the apparatus at a predetermined cutting speed during the cutting operation and at a relatively high 80 speed during transport, of supplemental propelling means for the apparatus operable independently of truck wheel drive for propelling the apparatus at substantially the same speeds.

5. The combination with a mining apparatus of the wheel mounted type adapted to run along a mine trackway and having cutting mechanism adapted to operate while said apparatus is supported and guided by the 90 mine trackway and mechanism for driving the truck wheels to propel the apparatus at a predetermined cutting speed during the cutting operation and at a relatively high speed during transport, of supplemental propelling means for the apparatus operable independently of truck wheel drive for propelling the apparatus at substantially the same speeds and including a winding device and a cooperating draft element.

6. The combination with a mining apparatus of the wheel mounted type adapted to run along a mine trackway and having cutting mechanism adapted to operate while said apparatus is supported and guided by the mine trackway and mechanism for driving the truck wheels to propel the apparatus at a predetermined slow cutting speed during the cutting operation, of supplemental propelling means for the apparatus operable independently of truck wheel drive for propelling the apparatus at a similar slow speed and including a plurality of independently operable winding devices and cooperating draft elements.

7. The combination with a mining apparatus of the wheel mounted type adapted to run along a mine trackway and having cutting mechanism adapted to operate while said apparatus is supported and guided by the mine trackway and mechanism including a motor for driving the truck wheels to propel the apparatus at a predetermined relatively low speed during the cutting operation and at a relatively high speed during transport, of supplemental propelling means for the apparatus to effect a continuous slow speed drive appropriate for cutting and at substantially the same speed as said predetermined low truck wheel driving speed, said 130

supplemental propelling means being driven by said motor and operable independently of truck wheel drive.

8. The combination with a mining apparatus of the wheel mounted type adapted to run along a mine trackway and having cutting mechanism adapted to operate while said apparatus is supported and guided by the mine trackway and mechanism including a motor for driving the truck wheels to propel the apparatus at a relatively low speed during the cutting operation and at a relatively high speed during transport, of supplemental propelling means for the apparatus for propelling the latter at substantially the same speed as said low truck wheel driving speed, said supplemental propelling means being driven by said motor and operable independently of truck wheel drive and including a winding device and a cooperating draft element, said winding device being arranged on a horizontal axis at one side of the apparatus.

9. The combination with a mining apparatus of the wheel mounted type adapted to run along a mine trackway and having a cutting mechanism adapted to operate while said apparatus is supported and guided by the mine trackway and mechanism including a motor for driving the truck wheels to propel the apparatus during the cutting operation, of supplemental propelling means for the apparatus for propelling the latter at substantially the same speed as said truck wheel driving speed, said supplemental propelling means being driven by said motor and operable independently of truck wheel drive and including a plurality of independently operable winding devices and cooperating draft elements.

10. In a mining apparatus, a wheeled truck adapted to run along a mine trackway, cutting mechanism carried by said truck and adapted to operate while supported thereon and propelled thereby, a motor on said truck, mechanism driven by said motor for driving the truck wheels to propel the apparatus along the mine trackway to effect continuous slow speed drive appropriate for cutting, and supplemental propelling mechanism operable independently of truck wheel drive for propelling the apparatus at substantially the same speed as said slow truck wheel driving speed, said supplemental propelling mechanism being driven by said motor, said supplemental mechanism including a haulage device and a cooperating haulage cable.

11. In a mining apparatus, a wheeled truck adapted to run along a mine trackway, cutting mechanism carried by said truck and adapted to operate while supported thereon and propelled thereby, a motor on said truck, mechanism driven by said motor for driving the truck wheels to propel the apparatus

along the mine trackway to effect feed of the cutting mechanism during the cutting operation, and supplemental propelling mechanism driven by said motor for propelling the apparatus at substantially the same speed as said truck wheel driving speed including independently operable haulage devices and cooperating haulage cables.

12. In a mining apparatus, a wheeled truck adapted to run along a mine trackway, cutting mechanism carried by said truck and adapted to operate while supported thereon and propelled thereby, a motor on said truck, mechanism including a speed control clutch driven by said motor for driving the truck wheels to propel the apparatus along the mine trackway, and supplemental propelling mechanism operable independently of said truck wheel driving mechanism and driven by said motor for propelling the apparatus at substantially the same speed as said truck wheel driving speed, said supplemental propelling mechanism being controlled by said speed controlling clutch and including a haulage device and a cooperating haulage cable.

13. In a mining apparatus, a wheeled truck adapted to run along a mine trackway, cutting mechanism carried by said truck and adapted to operate while supported thereon and propelled thereby, a motor on said truck, mechanism including a speed control clutch driven by said motor for driving the truck wheels to propel the apparatus along the mine trackway, and supplemental propelling mechanism driven by said motor and controlled by said speed controlling clutch including a plurality of independently or simultaneously operable haulage devices and cooperating haulage cables.

14. In a mining apparatus, a wheeled truck adapted to run along a mine trackway, cutting mechanism carried by said truck and adapted to operate thereon while said truck is supported and guided by the mine trackway, a motor on said truck, mechanism driven by said motor for driving the truck wheels to propel the apparatus along the mine trackway at different speeds including plural predetermined speed gearing, and supplemental propelling mechanism operable independently of truck wheel drive and driven through said plural speed gearing, said supplemental mechanism including a winding device and a cooperating draft element for effecting propulsion of the apparatus at substantially the same speeds.

15. In a mining apparatus, a wheeled truck adapted to run along a mine trackway, cutting mechanism carried by said truck and adapted to operate thereon while said truck is supported and guided by the mine trackway, a motor on said truck, mechanism driven by said motor for driving the truck wheels to propel the apparatus along the mine track-

way including selective transmission gearing for driving the truck wheels at a predetermined cutting speed and at a relatively high transport speed, and supplemental propelling means operable independently of truck wheel drive and driven through said transmission gearing for effecting propulsion of the apparatus at substantially the same speeds.

16. In a mining apparatus, a wheeled truck adapted to run along a mine trackway, cutting mechanism carried by said truck and adapted to operate while supported thereon and propelled thereby, a motor on said truck, mechanism driven by said motor for driving the truck wheels to propel the apparatus along the mine trackway including transmission gearing for driving the truck wheels at a predetermined low cutting speed, and supplemental propelling means driven through said transmission gearing for propelling the apparatus at substantially the same speed as said low truck wheel driving speed including a plurality of independently operable winding devices and cooperating draft elements.

17. In a mining apparatus, a wheeled truck adapted to run along a mine trackway, cutting mechanism carried by said truck and adapted to operate while supported thereon and propelled thereby, a motor on said truck, mechanism driven by said motor including fast and slow predetermined speed gearing including fast and slow speed terminal gears for driving the truck wheels to propel the apparatus along the mine trackway at either a relatively high transport speed or a relatively low cutting speed, and supplemental propelling mechanism operable independently of truck wheel drive and driven through said gearing for propelling the apparatus at substantially the same speeds.

18. In a mining apparatus, a wheeled truck adapted to run along a mine trackway, cutting mechanism carried by said truck, a motor on said truck, mechanism driven by said motor including fast and slow predetermined speed gearing including fast and slow speed terminal gears for driving the truck wheels to propel the apparatus along the mine trackway at either a relatively high transport speed or a relatively low cutting speed, and supplemental propelling mechanism operable independently of truck wheel drive and driven through said gearing for propelling the apparatus at substantially the same speeds, said supplemental mechanism including a winding device and a cooperating draft element.

19. In a mining apparatus, a wheeled truck adapted to run along a mine trackway, cutting mechanism carried by said truck, a motor on said truck, mechanism driven by said motor including fast and slow speed gearing for driving the truck wheels to propel the apparatus along the mine trackway at either a

relatively high speed or at a relatively low speed, and supplemental propelling mechanism driven through said gearing for propelling the apparatus at similar high and low speeds, and including a plurality of winding devices and cooperating draft elements.

20. In a mining apparatus, a wheeled truck adapted to run along a mine trackway, cutting mechanism carried by said truck and adapted to operate while supported thereon and propelled thereby, a motor on said truck, mechanism driven by said motor for driving the truck wheels to propel the apparatus along the mine trackway to effect feed of the cutting mechanism during the cutting operation, and supplemental propelling means including a plurality of independently or simultaneously operable winding devices arranged on transverse axes at opposite sides of the truck, and cables cooperating with said winding devices, said devices being operable to propel the apparatus along the mine trackway in either direction.

21. In a mining apparatus, a wheeled truck adapted to run along a mine trackway, cutting mechanism carried by said truck and adapted to operate while supported thereon and propelled thereby, a motor on said truck, mechanism driven by said motor including fast and slow speed gearing for driving the truck wheels to propel the apparatus along the mine trackway at either a relatively high speed or at a relatively low speed, and supplemental propelling mechanism driven through said gearing for propelling the apparatus at similar speeds, and including a plurality of winding devices and cooperating draft elements.

22. The combination with a mining apparatus of the wheel mounted type adapted to run along a mine trackway and having cutting mechanism adapted to operate while said apparatus is supported and guided by the mine trackway and mechanism for driving the truck wheels to propel the apparatus along the mine trackway at a predetermined relatively slow speed during the cutting operation and at a relatively high speed during transport and including a fast speed gear train and a slow speed gear train, said gear trains including fast and slow speed terminal gears, of supplemental propelling means for the apparatus operable independently of truck wheel drive and driven at similar speeds through said fast and slow speed gear trains.

23. The combination with a mining apparatus of the wheel mounted type adapted to run along a trackway and having cutting mechanism adapted to operate while said apparatus is supported and guided by the mine trackway and mechanism for driving the truck wheels to propel the apparatus along the mine trackway at a predetermined relatively slow speed during the cutting operation and

at a relatively high speed during transport and including a fast speed gear train and a slow speed gear train, said gear trains including fast and slow speed terminal gears 5 and clutches for selectively rendering the terminal gears of said gear trains operative, of supplemental propelling means for the apparatus operable independently of truck wheel drive and driven at similar speeds 10 through said fast and slow speed gear trains and under the control of said clutches.

24. The combination with a mining apparatus of the wheel mounted type adapted to run along a mine trackway and having cutting 15 mechanism adapted to operate while said apparatus is supported and guided by the mine trackway and mechanism for driving the truck wheels to propel the apparatus along the mine trackway at a relatively slow speed during the cutting operation including a slow speed gear train and a friction controlling clutch, of supplemental propelling means for the apparatus operable independently of truck wheel drive and driven at 20 similar speeds through said slow speed gear train and under the control of said friction clutch.

25. The combination with a mining apparatus of the wheel mounted type adapted to run along a mine trackway and having cutting mechanism adapted to operate while said apparatus is supported and guided by the mine trackway, and mechanism for driving the truck wheels to propel the apparatus 30 along the mine trackway at a relatively slow speed during cutting operation and at a relatively high speed during transport and including a fast speed gear train and a slow speed gear train and friction clutches, one individual to each gear train, for selectively rendering said gear trains operative, of supplemental propelling means for the apparatus operable independently of truck wheel drive and driven at similar speed through 40 said fast and slow speed gear trains and under the control of said friction clutches.

26. The combination with a mining apparatus of the wheel mounted type adapted to run along a mine trackway and having cutting mechanism adapted to operate while said apparatus is supported and guided by the mine trackway and mechanism for driving the truck wheels to propel the apparatus along the mine trackway at a relatively slow speed during the cutting operation and at a relatively high speed during transport and including a fast speed gear train and a slow speed gear train, each having a terminal driving element, and friction clutches for each 55 terminal element for selectively connecting said gear trains in driving relation with the truck wheels, of supplemental propelling means for the apparatus operable independently of truck wheel drive and driven at similar speeds through said fast and slow speed

gear trains and under the control of said friction clutches.

27. The combination with a mining apparatus of the wheel mounted type adapted to run along a mine trackway and having cutting mechanism adapted to operate while said apparatus is supported and guided by the mine trackway and mechanism for driving the truck wheels to propel the apparatus along the mine trackway at a relatively slow speed during the cutting operation and at a relatively high speed during transport and including devices for effecting drive of the truck wheels at either high or low predetermined speeds, of supplemental propelling means for the apparatus operable independently of truck wheel drive and driven at similar speeds through said driving mechanism and including a friction controlling clutch for connecting said supplemental controlling means in driving relation with said driving devices at will. 70

28. The combination with a mining apparatus of the wheel mounted type adapted to run along a mine trackway and having cutting mechanism adapted to operate while said apparatus is supported and guided by the mine trackway and mechanism for driving the truck wheels to propel the apparatus along the mine trackway at a slow cutting speed during the cutting operation, of supplemental propelling means for the apparatus operable independently of truck wheel drive and driven at a similar speed and including a winding device disposed on a horizontal axis extending transversely of the apparatus at one side of the apparatus and a co-operating draft element. 90

29. The combination with a mining apparatus of the wheel mounted type adapted to run along a mine trackway and having cutting mechanism adapted to operate while said apparatus is supported and guided by the mine trackway and mechanism for driving the truck wheels to propel the apparatus along the mine trackway at a relatively slow speed during the cutting operation and a relatively high speed during transport and including a fast speed worm gear train and a slow speed worm gear train, of supplemental propelling means for the apparatus operable independently of truck wheel drive and driven at similar speeds through said fast and slow speed worm gear trains. 105

30. The combination with a mining apparatus of the wheel mounted type adapted to run along a mine trackway and having cutting mechanism adapted to operate while said apparatus is supported and guided by the mine trackway and mechanism for driving the truck wheels to propel the apparatus along the mine trackway at a relatively slow speed during the cutting operation and at a relatively high speed during transport and including a fast speed worm gear train and 115

a slow speed worm gear train each including a terminal worm wheel and friction clutches for selectively connecting said gear trains in driving relation with the truck wheels, of supplemental propelling means for the apparatus operable independently of truck wheel drive and driven at similar speeds through said fast and slow speed worm gear trains and under the control of said friction clutches.

31. The combination with a mining apparatus of the wheel mounted type adapted to run along a mine trackway and having cutting mechanism adapted to operate while said apparatus is supported and guided by the mine trackway and mechanism for driving the truck wheels to propel the apparatus along the mine trackway at a relatively slow speed during the cutting operation and at a relatively high speed during transport and including a fast speed gear train and a slow speed gear train having coaxial terminal gears, and a clutch controlling each terminal gear, of supplemental propelling means for the apparatus operable independently of truck wheel drive and driven at similar speeds through said fast and slow speed gear trains and under the control of said clutches.

32. The combination with a mining apparatus of the wheel mounted type adapted to run along a mine trackway and having cutting mechanism adapted to operate while said apparatus is supported and guided by the mine trackway and mechanism for driving the truck wheels to propel the apparatus along the mine trackway at a relatively slow speed during cutting operation and at a relatively high speed during transport and including a fast speed gear train and a slow speed gear train having coaxial terminal gears, a shaft coaxial with said terminal gears and clutches for selectively connecting said terminal gears with said shaft, of supplemental propelling means for the apparatus operable independently of truck wheel drive and driven at similar speeds from said shaft under the control of said clutches.

33. The combination with a mining apparatus of the wheel mounted type adapted to run along a mine trackway and having cutting mechanism adapted to operate while said apparatus is supported and guided by the mine trackway and mechanism for driving the truck wheels to propel the apparatus along the mine trackway at a relatively slow speed during cutting operation and at a relatively high speed during transport and including a fast speed gear train and a slow speed gear train having coaxial terminal gears, a shaft coaxial with said terminal gears and clutches for selectively connecting said terminal gears with said shaft, of separately operable supplemental propelling devices for said apparatus operable independently of truck wheel drive and driven at similar

speeds through said fast and slow speed gear trains from the opposite ends of said shaft.

34. The combination with a mining apparatus of the wheel mounted type adapted to run along a mine trackway and having cutting mechanism adapted to operate while said apparatus is supported and guided by the mine trackway and mechanism for driving the truck wheels to propel the apparatus along the mine trackway at a relatively slow speed during the cutting operation and at a relatively high speed during transport and including a fast speed gear train and a slow speed gear train having coaxial terminal gears, a shaft coaxial with said gears, and clutches for selectively connecting said terminal gears with said shaft, said truck wheels being driven from one end of said shaft, of supplemental propelling means for the apparatus operable independently of truck wheel drive and driven from the opposite ends of said shaft at similar speeds through said fast and slow speed gear trains and under the control of said clutches.

35. The combination with a mining apparatus of the wheel mounted type adapted to run along a mine trackway and having cutting mechanism adapted to operate while said apparatus is supported and guided by the mine trackway and mechanism for driving the truck wheels to propel the apparatus along the mine trackway at a relatively slow speed during the cutting operation and at a relatively high speed during transport and including a fast speed gear train and a slow speed gear train having coaxial terminal gears, a shaft coaxial with said gears, and clutches for selectively connecting said terminal gears with said shaft, said truck wheels being driven from one end of said shaft, of supplemental propelling means for the apparatus operable independently of truck wheel drive and driven from the opposite end of said shaft at similar speeds through said fast and slow speed gear trains and under the control of said clutches, said supplemental propelling means including a friction clutch for connecting the same at will in driving relation with said shaft.

36. The combination with a mining apparatus of the wheel mounted type adapted to run along a mine trackway and having cutting mechanism adapted to operate while said apparatus is supported and guided by the mine trackway, and including a kerf cutter disposable in horizontal and vertical cutting positions, and mechanism for driving the truck wheels to propel the apparatus along the mine trackway during the cutting operation while said kerf cutter is in either of its operating positions, of supplemental propelling means for the apparatus operable independently of truck wheel drive for propelling the apparatus during cutting.

37. The combination with a mining ap-

paratus of the wheel mounted type adapted to run along a mine trackway and having cutting mechanism adapted to operate while said apparatus is supported and guided by the mine trackway and including a kerf cutter disposable in horizontal and vertical cutting positions and mechanism for driving the truck wheels to propel the apparatus along the mine trackway during the cutting operation while said kerf cutter is in either 10 of its operating positions, of supplemental propelling means for the apparatus operable independently of truck wheel drive for propelling the apparatus during cutting, and including a cable winding device and a cooperating draft cable.

38. The combination with a mining apparatus of the wheel mounted type adapted to run along a mine trackway and having cutting mechanism adapted to operate while said apparatus is supported and guided by the mine trackway and mechanism for driving the truck wheels to propel the apparatus along the mine trackway during the cutting operation, of supplemental propelling means for the apparatus operable independently of truck wheel drive and driven at a similar speed and including a cable winding device disposed at one side of the apparatus, and a 25 cooperating draft cable.

39. The combination with a mining apparatus of the wheel mounted type adapted to run along a mine trackway and having cutting mechanism adapted to operate while said apparatus is supported and guided by the mine trackway and mechanism for driving the truck wheels to propel the apparatus along the mine trackway during the cutting operation, of supplemental propelling means for the apparatus operable independently of 35 truck wheel drive and driven at a similar speed and including independently operable cable winding devices arranged at opposite sides of the longitudinal median line of the apparatus, and draft cables cooperating with 40 said winding devices respectively.

40. The combination with a mining apparatus of the wheel mounted type adapted to run along a mine trackway and having cutting mechanism adapted to operate while 50 said apparatus is supported and guided by the mine trackway, and mechanism for propelling the apparatus along the mine trackway during the cutting operation, of supplemental propelling means for the apparatus operable independently of propulsion by said first mentioned propelling mechanism and driven at a similar speed, and including a winding device disposed on a horizontal 55 axis on one side of the apparatus and a co-operating draft element.

41. The combination with a mining apparatus of the wheel mounted type adapted to run along a mine trackway and having cutting mechanism adapted to operate while 60

said apparatus is supported and guided by the mine trackway and propelling mechanism for the apparatus, of supplemental mechanism for propelling the apparatus bodily along the mine trackway during the cutting 70 operation including independently or simultaneously operable, relatively rotatable cable winding devices and cooperating draft cables.

42. The combination with a mining apparatus of the wheel mounted type adapted to run along a mine trackway and having cutting mechanism adapted to operate while said apparatus is supported and guided by the mine trackway and mechanism for driving the truck wheels to propel the apparatus at a predetermined relatively low speed during the cutting operation and at a relatively high speed during transport, of supplemental propelling means for the apparatus 80 to effect a continuous slow speed drive appropriate for cutting and at substantially the same speed as said slow truck wheel driving speed, said supplemental propelling means including means for rendering said supplemental means inoperative during operation of said truck wheel driving mechanism.

43. The combination with a mining apparatus of the wheel mounted type adapted to run along a mine trackway and having cutting mechanism adapted to operate while said apparatus is supported and guided by the mine trackway and mechanism for driving the truck wheels to propel the apparatus at a relatively low speed during the cutting operation and at a relatively high speed during transport, of supplemental propelling means for the apparatus for propelling the latter at substantially the same speed as said 90 low truck wheel driving speed and including a winding device arranged at a horizontal axis at one side of the apparatus and a co-operating draft element and means for rendering said winding device inoperative during operation of said truck wheel driving mechanism.

44. The combination with a mining apparatus of the wheel mounted type adapted to run along a mine trackway and having cutting mechanism adapted to operate while said apparatus is supported and guided by the mine trackway and mechanism for driving the truck wheels to propel the apparatus at a predetermined cutting speed during the cutting operation and at a relatively high speed during transport, of supplemental propelling means for propelling the apparatus at substantially the same speeds and including means for rendering said supplemental means inoperative during operation of said truck wheel driving mechanism.

45. The combination with a mining apparatus of the wheel mounted type adapted to run along a mine trackway and having cut- 125

ting mechanism adapted to operate while said apparatus is supported and guided by the mine trackway and mechanism for driving the truck wheels to propel the apparatus 5 along the mine trackway during the cutting operation, of supplemental propelling means for the apparatus for supplementing the truck wheel propulsion mechanism during the cutting operation including a cable winding drum and a cooperating haulage cable and mechanism for driving said haulage drum including a transverse shaft, a second transverse shaft coaxial with said drum, said drum being mounted for rotation relative to 10 said shaft, and transmission connections including bevel gearing connecting said shafts in driving relation.

46. The combination with a mining apparatus of the wheel mounted type adapted to 20 run along a mine trackway and having cutting mechanism adapted to operate while said apparatus is supported and guided by the mine trackway and mechanism for driving the truck wheels to propel the apparatus 25 along the mine trackway at a slow cutting speed during the cutting operation, of supplemental propelling means for the apparatus for supplementing the truck wheel propulsion mechanism during the cutting operation 30 and at substantially the same speed as said slow truck wheel driving speed, said supplemental propelling means including a cable winding drum and a cooperating haulage cable and mechanism for driving said haulage 35 drum including a transverse shaft and a friction clutch for connecting said drum and shaft in driving relation.

47. The combination with a mining apparatus of the wheel mounted type adapted to 40 run along a mine trackway and having cutting mechanism adapted to operate while said apparatus is supported and guided by the mine trackway and mechanism for driving the truck wheels to propel the apparatus 45 along the mine trackway during the cutting operation, of supplemental propelling means for the apparatus for supplementing the truck wheel propulsion mechanism during the cutting operation including a cable winding drum and a cooperating haulage cable and mechanism for driving said haulage 50 drum including a transverse shaft, a friction clutch for connecting said drum and shaft in driving relation, and a control member 55 threadedly connected to the outer extremity of said shaft for controlling said friction clutch.

48. The combination with a mining apparatus of the wheel mounted type adapted to 60 run along a mine trackway and having cutting mechanism adapted to operate while said apparatus is supported and guided by the mine trackway and mechanism for driving the truck wheels to propel the apparatus 65 along the mine trackway at a slow cutting

speed during the cutting operation, of supplemental propelling means for the apparatus for supplementing the truck wheel propulsion mechanism during the cutting operation and at substantially the same speed as 70 said slow truck wheel driving speed, said supplemental propelling means including a cable winding drum and a cooperating haulage cable and mechanism for driving said haulage drum including a transverse shaft, a friction 75 clutch for connecting said drum and shaft in driving relation and means for controlling said clutch, said truck wheel driving mechanism including a chain driving sprocket operatively connected to the truck wheels and also 80 driven by said transverse shaft.

49. The combination with a mining apparatus of the wheel mounted type adapted to run along a mine trackway and having cutting mechanism adapted to operate while 85 said apparatus is supported and guided by the mine trackway and mechanism for driving the truck wheels to propel the apparatus at a predetermined cutting speed during the cutting operation, of supplemental 90 propelling means for the apparatus operable independently of truck wheel drive for propelling the apparatus at a similar speed and including a plurality of independently or simultaneously operable winding devices and 95 cooperating draft elements.

50. The combination with a mining apparatus of the wheel mounted type adapted to run along a mine trackway and having a cutting mechanism adapted to operate while 100 said apparatus is supported and guided by the mine trackway and mechanism including a motor for driving the truck wheels to propel the apparatus during the cutting operation, of supplemental propelling means for the apparatus driven by said motor and operable independently of truck wheel drive and including a plurality of independently or simultaneously operable winding devices and 105 cooperating draft elements.

51. In a mining apparatus, a wheeled truck adapted to run along a mine trackway, cutting mechanism carried by said truck and adapted to operate while supported thereon and propelled thereby, a motor on said truck, 113 mechanism driven by said motor for driving the truck wheels to propel the apparatus along the mine trackway to effect feed of the cutting mechanism during the cutting operation, and supplemental propelling mechanism driven by said motor including independently or simultaneously operable haulage devices and cooperating haulage cables. 118

52. In a mining apparatus, a wheeled truck adapted to run along a mine trackway, cutting mechanism carried by said truck and adapted to operate while supported thereon and propelled thereby, a motor on said truck, mechanism driven by said motor for driving the truck wheels to propel the apparatus 123 128 133

along the mine trackway including transmission gearing for driving the truck wheels at a predetermined cutting speed, and supplemental propelling means driven through said transmission gearing including a plurality of independently or simultaneously operable winding devices and cooperating draft elements.

53. In a mining apparatus, a wheeled truck adapted to run along a mine trackway, cutting mechanism carried by said truck, a motor on said truck, mechanism driven by said motor including fast and slow speed gearing for driving the truck wheels to propel the apparatus along the mine trackway at either a relatively high speed or at a relatively low speed, and supplemental propelling mechanism driven through said gearing for propelling the apparatus at similar speeds, and including a plurality of independently or simultaneously operable winding devices and cooperating draft elements.

In testimony whereof I affix my signature.
CHARLES F. OSGOOD.

CERTIFICATE OF CORRECTION.

Patent No. 1,849,310.

Granted March 15, 1932, to

CHARLES F. OSGOOD.

It is hereby certified that error appears in the printed specification of the above numbered patent requiring correction as follows: Page 1, line 71, before the syllable "al-" insert the words and comma now matured into Patent No. 1,785,961, patented Dec. 23, 1930.; same page, lines 86 and 87, strike out the words "or to be tilted" and insert the words and tilting, and line 98, for "mechanism" read mechanisms; page 2, line 118, for "hauling" read haulage; page 3, line 61, for "forward" read forwardly; and that the said Letters Patent should be read with these corrections therein that the same may conform to the record of the case in the Patent Office.

Signed and sealed this 31st day of May, A. D. 1932.

(Seal)

**M. J. Moore,
Acting Commissioner of Patents.**
